Primary Examiner — Jonathan J Han*Assistant Examiner* — Amanda J Berlinski(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken lines immediately adjacent to the shaded area define the bounds of the claimed design and form no part thereof. The five broken line circles within the shaded area represent eyelets which form no part of the claimed design. The broken lines depicting the remainder of the shoe form no part of the claimed design.
